Attorney.

UNITED STATES PATENT OFFICE.

THOMAS OLINGER, OF HOLLAND, MICHIGAN, ASSIGNOR TO FEDERAL STAMPING COMPANY, OF HOLLAND, MICHIGAN, A CORPORATION OF MICHIGAN.

FURNACE-REGISTER.

1,399,985.

Specification of Letters Patent. Patented Dec. 13, 1921.

Application filed January 3, 1921. Serial No. 434,415.

To all whom it may concern:

Be it known that I, THOMAS OLINGER, a citizen of the United States of America, residing at Holland, in the county of Ottawa

5 and State of Michigan, have invented certain new and useful Improvements in Furnace-Registers; and I do hereby declare the following to be a full, clear, and exact description of the invention, such as will 10 enable others skilled in the art to which it appertains to make and use the same.

This invention relates to a register adapted to be placed at the exit of hot air pipes of furnaces, covering the same where it 15 comes to a room which is heated thereby. Such registers in use are designed to be adjustable so as to pass a greater or less amount of hot air, being equipped with a movably mounted closure which may be 20 placed in different positions, either to completely shut off the entrance of hot air from the furnace pipe or fully open to permit the passage of the maximum amount of heated air, or at any intermediate position 25 as desired to suit conditions of the room. It is a primary object and purpose of the present invention to make a register of this character entirely of sheet metal, of a minimum number of parts and one in which all 30 parts may be stamped readily from sheet metal by use of suitable dies, and one in which the parts are very easily and quickly assembled substantially without the use of tools. A further object of the invention is 35 to make a register of this type in which the closure may be easily operated to any desired position and which will be frictionally held in such position through spring pressure continuously applied, but which is released when an application of force is made 40 to the operating member of said closure, thereby permitting the movement of the closure free of said spring pressure. Many other objects and purposes than those enu- 45 merated will appear as understanding of the invention is had from the following description, taken in connection with the accompanying drawing, in which,

Figure 1 is a front elevation of the 50 register.

Fig. 2 is a side elevation thereof.

Fig. 3 is an enlarged vertical transverse section through the register substantially on the plane of line 3—3, of Fig. 1.

55 Fig. 4 is a fragmentary rear elevation of

the register at the middle upper portion thereof.

Fig. 5 is a horizontal section on line 5—5, of Fig. 4.

Fig. 6 is a view similar to Fig. 4 but toward one end of the register, illustrating the means used to hingedly connect the closure to the body of the register, and

Fig. 7 is a fragmentary vertical section on the plane of line 7—7, of Fig. 6.

Like reference characters refer to like parts in the different figures of the drawing.

In the construction of the register, a plate 1 of sheet metal is used, rectangular in outline and formed a short distance below 70 its upper edge with a horizontal rib 2 convexed on its outer side and recessed on its rear side, similar vertical ribs 3 parallel- 75 ing the vertical edges of the plate, and a lower rib 4 paralleling the lower edge there- of as shown. The space inclosed by ribs 2, 3 and 4 is made into a grating, parallel horizontal bars 5 and parallel intersecting vertical bars 6 being formed from the metal of the plate, as shown, the metal between said 80 bars being removed to provide openings for the passage of the heated air through the register. Adjacent each end of the upper rib 2 a rearwardly extending tang 7 is made, the same being integral with and extending 85 from the lower edge of the rib, the purpose of which will hereafter appear. Between the two central vertical bars 6 of the grating and where the same join the upper rib 2, two substantially triangular shaped in- 90 tegral sections 8 are left to serve as stops to limit the movement of the operating handle of the closure as will later appear.

The closure member for the register comprises a plate 9 of sheet metal formed at its 95 upper edge with a rolled bead 10 of a shape and size to fit into the concaved recess in the rear side of rib 2. Adjacent each end and immediately below the bead 10, openings 11 are cut through which the tangs 7 may 100 pass being afterward curved upwardly as indicated in Fig. 7, to permanently secure the closure plate in hinged relation to the plate 1 in which the grating is made. Plate 9 at its lower and side edges is formed with 105 forwardly turned flanges 9^a which, in the closed position of the closure plate enter the recesses in the back of ribs 3 and 4, as is obvious.

An operating handle member is used for 110

moving the closure plate to different positions. This member comprises a sheet metal relatively narrow plate 12, formed at its lower end with rearwardly turned, downwardly projecting and spaced apart projections 13 adapted to pass through two openings 14 cut in the closure plate. Adjacent its upper end, this handle member is widened as indicated at 15 whereby two shoulders 16 are provided which, in the opening of the closure member come into contact with the sections 8, heretofore described, to limit the extent of opening of the closure plate. A tongue 17 is cut from the handle member and turned rearwardly, passing through an opening 18 in plate 9 and at its free end being turned upwardly, as shown at 19. A leaf spring 20 is located against the rear side of the closure plate 9, the tongue 17 passing through an opening 21 therein with the upturned part 19 lying against the rear side of the spring and holding it from disengagement. The effect of the spring is to normally draw the handle member 12 against the rib 2, and in practice, preferably, the handle member is curved, as at 22 to conform partially to the shape of the rib 2, giving a larger bearing between them.

30. It is evident that with a construction of this character, the closure plate may be moved to any desired position between two limits and held therein, the spring 20 drawing handle member 12 against the rib 2 causing a binding thereagainst which serves to hold the closure plate against movement. When it is desired to move the closure plate to a different position, it is necessary merely to press on the widened end 15 of the handle member 12. In opening the closure plate, the downward pressure on the member 12 compresses the spring 20 and frees the member from engagement with the rib 2 with a resultant elimination of frictional engagement therewith during the movement of the closure plate to a new position.

This construction of register is simple, consisting of four parts only, three of which are made from sheet metal and stamped and formed readily with dies. The spring is likewise easily produced. The assembly is simple, the only parts requiring any changing in assembling being the tangs 7 which are bent around the bead 10 of the closure plate. All of the other assembling operations consist of merely placing the parts together. The register made is light, yet strong and durable in service. The appended claims define the invention and I consider myself entitled to all forms of structure falling within their scope.

I claim:

1. In combination, a relatively fixed plate having an open grating formed therein and provided a short distance below its upper

edge and at the upper portion of the grating with a horizontal rib having a longitudinal recess in its rear side, a closure plate formed at its upper edge with a bead for seating in said recess, means for securing the bead in said recess, an operating handle member attached at its lower end to the closure member at a point below the rib and extending upwardly through the grating in front of the rib, a tongue extending rearwardly from the operating member through the closure member, and spring means disposed between the rear side of the closure member and the end of the tongue for normally drawing said operating member toward the closure member and holding the operating member in contact with said rib, substantially as described.

2. In combination, a relatively fixed plate formed with an open grating and provided a short distance below its upper edge at the upper portion of the grating with a forwardly projecting horizontal rib having a longitudinal recess in its rear side, a closure plate formed at its upper edge with a bead seating in said recess, means on the first plate passing through the closure plate and around the bead to secure the same hingedly together, an operating member attached at its lower end to the closure plate and extending upwardly through the grating and in front of the rib, and spring means operatively connected to the closure plate and operating member for normally holding the operating member against the rib, substantially as described.

3. In combination, a relatively fixed plate formed with an open grating, a closure plate hingedly connected at its upper edge to and on the rear side of the first plate, said closure plate being adapted to close the grating, an operating handle attached to the closure plate and extending upwardly through the grating, and spring means acting on the operating handle to normally draw the same into frictional engagement with the first plate, substantially as described.

4. In combination, a relatively fixed plate formed with an open grating, a closure plate hingedly connected at its upper edge to and on the rear side of the first plate, an operating handle attached at its lower end to the closure plate and extending upwardly through the grating, means on the operating handle extending rearwardly through the closure plate, and spring means disposed between the rear side of the closure plate and said means on the handle acting to normally draw the handle against the first plate to frictionally engage the handle therewith, substantially as and for the purposes described.

5. In combination, a sheet metal plate formed with an open grating at short distances inward from its edges, a sheet metal

closure plate hingedly connected at its upper edge to the rear side of the first plate at the upper side of the grating, a sheet metal operating handle formed with spaced apart 5 projections at its lower end extending through the closure plate, said handle extending upwardly through the grate, and spring means attached to the handle and acting to draw the handle toward the closure 10 plate and hold the handle in frictional contact with the first plate at the upper portion of the grating.

6. A structure containing the elements defined in combination in claim 5, in which 15 said operating handle is widened at its upper portion thereby making shoulders at the lower part of said widened portion, and sections on the grating adapted to act as stops against which said shoulders engage 20 when the closure plate is turned rearwardly to a predetermined position.

7. In combination, a sheet metal plate formed with an open grating set in short distances from its edges, a sheet metal closure 25 plate hingedly connected at its upper edge to the rear side of the first plate at the upper side of the grating, a sheet metal operating handle formed with spaced apart projections at its lower end extending 30 through openings in the closure plate, said handle extending upwardly through the grating, a tongue struck rearwardly from the handle a short distance below the hinged

connection of the closure plate to the first plate and passing through an opening in 35 the closure plate, said tongue at its free end being bent at right angles to its main portion, and a leaf spring disposed between said bent end of the tongue and the rear side of the closure plate, substantially as described. 40

8. In combination, a sheet metal plate formed with an open grating set in short distances from its edges, and being provided at the upper part of the grating with a horizontal rib having a longitudinal recess in its 45 rear side, a sheet metal closure plate formed at its upper edge with a rolled bead seating in said recess, tangs integral with the rib passing rearwardly through the closure plate and bent upwardly around the bead 50 thereof, a sheet metal operating handle formed with spaced apart projections at its lower end extending through openings in the closure plate, said handle extending upwardly through the grating, a tongue struck 55 rearwardly from the handle a short distance below the connection of the closure plate to the first plate and passing through an opening in the closure plate, a leaf spring located against the rear side of the closure plate, 60 said tongue passing therethrough, and means at the end of the tongue for holding the spring against the closure plate, substantially as described.

In testimony whereof I affix my signature. 65
THOMAS OLINGER.
